COMBINED COOKER AND COOLER

Filed April 4, 1925

2 Sheets-Sheet 2

Fig. 2.

UNITED STATES PATENT OFFICE.

NELSON H. FOOKS, OF PRESTON, MARYLAND.

COMBINED COOKER AND COOLER.

Application filed April 4, 1925. Serial No. 20,788.

To all whom it may concern:

Be it known that I, NELSON H. FOOKS, a citizen of the United States, residing at Preston, in the county of Caroline and State of Maryland, have invented certain new and useful Improvements in Combined Cookers and Coolers; and I do hereby declare the following to be a full, clear, and exact description of the invention, such as will enable others skilled in the art to which it appertains to make and use the same.

This invention relates to apparatus for continuously cooking and cooling substances packed in sealed containers, such as cans, and it is an object of the invention to provide an apparatus for the purpose indicated which shall comprise two separate helical can paths, in contiguous relation, the cans being moved along one of these paths while the contents of the cans are being cooked and moved along the other path while being cooled, both of said helical can paths being housed within a shell or container so constructed that there is direct open communication between the two said paths. The path along which the cans are moved while the contents thereof are being cooled will be submerged or partially submerged in cooling water while the other said path will be in a zone subject to the direct action of the heating medium which will preferably be steam, the latter overlying the body of cooling water. To permit the cans to pass from the can path in the cooking zone to the other can path, passages are provided in adjacent portions of said paths so that the cans may pass directly from one path to the other.

It is also an object of the invention to provide an apparatus which will permit the cans to be transferred from the path in the cooking zone to the path in the cooling zone at different points along the first named path to the end that the length of time the cans are in the cooking zone may be varied to suit the substances being processed. In carrying out this feature of the invention a plurality of passages are provided in adjacent sections of the paths, the passages being opened or closed by suitable gates or slides as will more fully appear by reference to the drawings and detailed description thereof.

More particularly the invention has for its object to provide an apparatus which

will permit the efficient practice of the processes set forth in my prior Patents, Numbers, 1,354,962; 1,491,902; and 1,491,903.

Various other features of invention will appear as the description progresses.

Referring to the drawings:

Fig. 1 is a view partly in side elevation and partly in section showing the improved cooking and cooling apparatus;

Fig. 2. is an end elevation of Fig. 1. viewed from the right, part of the shell or container being broken away to expose the interior mechanism, parts of the latter being in section;

Fig. 3. is a section on line 3—3 of Fig. 4. 70

Fig. 4. is a cross section taken on line 4—4 of Fig. 3;

Fig. 5. is a vertical cross section taken on line 5—5 of Fig. 1.

In the drawings 1 indicates a shaft to 75 which is secured a cylindrical reel generally indicated at 2, said reel being provided with a series of longitudinally extending angle bars 3 maintained in spaced relation to form channels 4 in which the cans 5 may be received and guided longitudinally or parallel with the shaft 1 by means hereinafter explained.

Surrounding the reel 2 is a helical can path or track generally indicated at 6, said can path being conveniently made of angle irons 7, as for example, T-iron.

Mounted on a shaft 8 is a reel 9, and surrounding the reel is a helical can path or track 10, this reel and can path being constructed in substantially the same manner as the other reel and helical can path already mentioned.

The helical can path 10 and its interior reel 9, are located at the bottom of a suitable tank or shell 11, the shaft 8 of the reel having suitable bearings in the upright walls of the tank as indicated at 12. The helical can path 6 is superposed on the helical can path 10. The shaft 1 of the reel within the helical can path 6, is suitably supported in bearings 13 in the side walls of tank. Both helical can paths 6 and 10 are held in fixed position with respect to each other and with respect to the tank or container in which the same are contained in any suitable manner.

The shaft 1 on which the reel 2 is mounted is adapted to be rotated by any suitable source of power, not shown. The shaft 8

on which the reel 9 is mounted is geared to the shaft 1 preferably by means of an intermediate shaft 14 and bevel gears 15 as indicated in Fig. 1.

5 Filled cans 5 are entered into the shell or container 11 for initial passage along the helical can path 6 by a suitable rotary feed device 16 at the top of the tank; the cans being passed through a passage 17 in the 10 helical can path and received in the channel 4 formed by the spaced angle irons 3 extending longitudinally of the reel. The combined depth of the helical can path 6 and channel 4 is such that the cans will be received partly into both and consequently as the reel rotates the cans will be moved along said helical path from one end of the same to the other unless previously discharged therefrom.

20 The helical path 6 constitutes the path taken by the cans while the contents thereof are being cooked and the helical path 10 is the path being taken by the cans while they are being cooled after having been cooked.

25 The manner of passing the cans from the path or track 6 to the underlying track or can path 10 will now be explained.

Referring more particularly to Figs. 3 and 4, it will be seen that the adjacent sections 30 of the inwardly directed flanges of the T-irons are cut away to provide a direct passage 20 through which the cans 5 may pass from the upper to the lower track, the cans after passing through the opening or passage 35 being received in the channels formed by the radially extending flanges 3' of the angle-irons 3 along the reel 9. Rotation of the reel 9 moves the cans away from the opening or passage 20 and progresses them

40 along the helical track or path 10 as will now be understood. A plurality of similar can passages or openings between the two tracks 6 and 10 are provided at different points between the two tracks to permit 45 the distance travelled by the cans along the track 6 to be shortened and thus shorten the time during which the filled cans are subjected to the heating medium supplied for processing the filled cans. The various

50 passages 20 between said tracks are adapted to be closed by closure means which preferably take the form of plates or gates 21 which are provided with suitable extensions 21' to permit the gates or plates to be operated

55 from the exterior of the tank or container 11. The plate 21 is somewhat wider than the width between the upright walls 7' or the tracks, and is slidably supported between the two tracks 6 and 10 in the guideways 22 formed in a suitable fitting 23.

The plate 21 may be provided with a suitable stop 24 on its undersurface to prevent the same from being drawn too far out of the fitting. When the slide is closed the

slide while passing the same. It will be observed that the top of the slide is substantially flush with the can engaging surface of the track and hence no interference will be offered to the cans in passing the opening 20 when the slide is closed.

60 The means and mechanism for discharging the cans from the discharge end of the lower track 10 will now be described. The track 10 which underlies the track 6 and the reel 9 of the former are longer than the upper track and reel as shown in Fig. 1, and an extension 11' is provided on the tank to accommodate the extra length of track and reel.

65 Mounted on top of the tank extension 11' is a housing 25 within which is contained a rotary valve 26 having can receiving pockets 27 in its periphery, said rotary valve being tangentially disposed with respect to the track 10. The track 10 adjacent the rotary valve 26 is cut away as at 28 to permit cans to pass from the track into the pockets of the rotary valve. The cans 5 are lifted from the channels 4 in the reel 9, when they reach opening 28, by mechanism preferably of the type shown in my prior Patent #1,363,103 patented December 21, 1920, said mechanism including a fixed cam 29 which is adapted to move plungers 30 carried by the end of the reel 9 upwardly for a sufficient distance to elevate the cans 5 into the pockets 27 of the rotary valve 26. Further detailed description of this elevating mechanism is not considered necessary in view of the disclosure in the said patent. The housing 25 for the rotary valve 26 is provided with a discharge chute 31 for cans.

70 The rotary valve 26 is mounted on a shaft 32 which is suitably supported in bearings 33 in the said walls of the housing 25 and said valve is driven in the proper timely relation with respect to the reel 9 by any suitable mechanism as by means of an intermediate shaft 33 between the two shafts 8 and 32, bevel gears 34 connecting the shaft 33 to the shafts 8 and 32.

75 The track 10 constitutes the cooling path along which the cans are progressed after the contents thereof have been processed, and this track 10 is adapted to be submerged or partially submerged in a cooling liquid such as water indicated at 35. Cooled water is supplied to the bottom of the tank by any suitable conduit 36 and the level of the water is maintained by an overflow pipe 37 disposed at the proper level as shown in Fig. 2. If desired, a steam trap 38 may be provided in the pipe 37.

80 The track 6 constitutes the track along which the cans will be moved while the contents thereof are being processed. A conduit 39 is provided at any suitable point in the tank above the water level to supply

the heating medium for processing the filled cans. The heating medium will preferably be steam, but it is obvious that the apparatus is not limited to the use of any particular kind of gaseous heating medium. The gaseous heating medium will overlie the body of the cooling water and the pressure on the cooling water will, therefore, be substantially the same as that in the heating zone assuming that the heating medium is under pressure. The interchange of heat between the heating medium and cooling water will not be sufficient to interfere with the successful operation of the apparatus.

15 The present invention also discloses an apparatus which will permit filled cans to be processed for the desired length of time in a heating zone, the cans being carried around the helical can track while being processed.

20 After the cans have been processed for the desired length of time they pass from the track 6 to the adjacent track 10 through the openings 20 provided between the tracks. After passing from the track 6 to the track 25 10 the cans are discharged from the track 10 by rotary valve 26 from whence they are discharged into the atmosphere through the chute 31. It will further be seen that if the gate or slide 21 at the point *a* in the tank is opened the cans will pass through the opening 20 corresponding to the slide, and the length of time the cans are in the heating zone will be less than if they were allowed

to pass from the track 6 at the points *b* or *c*.

While the construction of the apparatus has been described with considerable particularity of detail, it will be appreciated that various changes can be made in the construction without departing from the spirit 40 of the invention.

What I claim is:

1. In combination, a pair of helical can tracks of different lengths, the track of shorter length being superposed on the other 45 one, the extra length of the longer track extending beyond one end of the shorter track, means for feeding cans to the shorter track, rotary means within both of said tracks for progressing the cans therealong, means for 50 passing cans from the shorter to the longer track at any given point between them comprising aligned openings in adjacent sections of the tracks, means for discharging the cans from the longer track comprising a rotary valve tangentially arranged on the extra length of the longer track, said valve adapted to receive the cans from the discharge end of the longer track.

2. The combination specified in claim 1, 55 said tracks being surrounded by a container adapted to contain liquid within which the longer track may be partially submerged.

In testimony whereof I affix my signature.

NELSON H. FOOKS.
